UNITED STATES PATENT OFFICE.

EDWIN S. THAYER, OF OAKDALE, PENNSYLVANIA.

TANK-CAR SIPHON VALVE.

Application filed January 26, 1925, Serial No. 4,712. Renewed December 29, 1927.

This invention relates to vehicle for conveying and dispensing liquids, such as tank cars, tank wagons, and the like, and is concerned more particularly with a tank construction for use in such vehicles provided with novel means for removing the contents therefrom. For purposes of illustration one form of the invention useful in connection with tank cars will be described, though it is to be understood that the utility of the mechanism is not limited to that particular application.

Tank cars as now commonly constructed include valves for controlling the flow of the contents therefrom and the usual tank car valve operates to stop the flow of the contents from the tank by a stopper-like action. The control of such valves is usually had by a long valve stem which is operable from the dome of a tank car. Usually such valve installations are reenforced against leakage of the contents of the tank in the event of defective valve seating or inoperativeness thereof. Such reenforcement is had by a relatively short pipe extension or casing below the valve, which is closed by a cap and washer to seal the outlet. All railroad companies experience considerable difficulty in preventing trouble of various kinds from arising on account of the tendency of all valve constructions of the stopper type to leak, become inoperative or easily damaged. This trouble is greatly increased because of the necessity of having to stop leakage from the valve into the pipe extension or casing by capping the casing, thus permitting a quantity of the tank contents to accumulate in the pipe extension below the tank where it may freeze, or where the extension may be liable to damage which would allow the contents of the tank to seep away onto the track. Not only because of actual loss of material is this objectionable, but also because of the danger which is created because of fire or explosion, particularly if the contents of the tank is of an inflammable character.

Objects of my invention are to produce an improved construction which will overcome the obvious objections to the usual tank valve construction, which is substantially free from relatively moving parts, which cannot leak, which cannot become materially damaged through carelessness or accident and which is of greatly reduced cost of installa-

tion with no cost involved for maintenance or repair.

These and other objects are attained in the tank siphon valve construction described in the following specification and illustrated in the accompanying drawing, in which:

Fig. 1 is a fragmental sectional view of a tank car tank equipped with a siphon valve construction embodying my invention.

Fig. 2 is a fragmental sectional view of a portion of a tank having a modified form of my invention applied thereto.

In the illustrated embodiment of my invention I show the body 3 of the tank in section, a dome 4 affording access to its interior through a closure 5. Within the tank and extending up into the dome somewhat is an inverted U-shaped element or siphon valve 6 which constitutes the principal element in the embodiment of my invention. This element partakes somewhat of the nature of a siphon in appearance as well as in operation during the tank emptying operation. The element 6 is secured in place within the tank. Both legs thereof are connected to openings in a casing 7 placed beneath the tank and in communication therewith to form a sump. This casing is provided with a chamber 8 which communicates with the interior of the tank through an opening 9, one leg 10 of the siphon valve communicating with chamber 8 while the other leg 11 communicates with an outlet extension 12 of the casing adjacent to the chamber. This outlet is closed by a cap 13. At the top of the valve a stop cock 14 is provided for purposes which will be described.

A slightly modified form of construction is illustrated in Fig. 2. In the arrangement there shown a sump casing similar to the casing 7 is secured to the bottom of the tank, this casing having a chamber 8' serving as a sump and in communication with the interior of the tank through a valve opening which may be closed by a valve 15. One leg 11 of the siphon element 6 is connected directly to the chamber 8', while the other leg 10 is connected to an outlet extension 12 which may be closed by a cap 13, as before.

The operation of the first described form of my invention consists in first closing the extension 12 with a cap 13 and then closing the stop cock 14. The tank is then filled. The resulting compression of the air in

siphon valve 6 will operate to permit the contents to rise only to the level indicated approximately by line 16, but even should the stop cock 14 or extension 12 be left open, 5 the contents can not flow out because it cannot rise over the bend of the valve above the level of the quantity in the tank. Thus any accidental emptying of the tank is prevented. To empty the tank any of three 10 methods may be employed. In one of these methods it is but necessary to remove cap 13 and then to subject the contents to pressure sufficient to force the fluid over the bend of the valve, after which siphonic action will 15 operate to empty the tank completely. In the other method the stop cock 14 is opened and the empty space in the branches 10 and 11 as well as the bend of the siphon valve are filled with the same fluid as is in the 20 tank, after which the opening of cap 13 will permit the entire tank contents to be drawn off siphonically. The third method of emptying the tank consists in removing the cap 13 and then subjecting the siphon valve 25 to suction from the outlet end.

With the construction illustrated in Fig. 2, additional control means for the flow of liquid are provided. When the contents of the tank are to be emptied, the valve 15 is 30 opened, whereupon the liquid enters the chamber 8' and flows upwardly in the leg 11 to a level such as that designated 16. By removing the cap 13, siphonic action may now be started in the usual manner, and such 35 siphonic flow will continue so long as the valve 15 remains open. If it should be desired to stop the flow, this can be accomplished by operating the valve 15 or by breaking the siphon by means of the valve 40 14, and the provision of the valve 15 simplifies the control of the flow when the siphon is to be started.

It will be noted that although the element 6 operates as a siphon under ordinary conditions, it is used for the additional purpose 45 of acting as a valve to prevent inadvertent emptying of the tank through damage or leakage resulting from wear or the parts getting out of adjustment. The siphon acts 50 as a seal against removal of the tank contents until such removal is desired, at which time the siphon is brought into action to remove the contents through the usual pipe connections.

55 Having thus described my invention what I claim is:

1. In combination with a tank car, a chamber located beneath the bottom of the tank and having two openings therein, a 60 siphon located within the tank with one leg occupying one of said openings, the opposite leg extending through and terminating beneath the bottom of the tank, the body of the siphon extending upwardly 65 within the tank and above the fluid level

within the tank, the second chamber opening communicating with the interior of the tank, a valve adapted to close the second opening, and a removable closure for the second mentioned leg of the siphon. 70

2. In combination with a tank, a siphon having its inlet leg mounted in a sump in the tank, and a valve for controlling the admission of liquid into the sump, the outlet leg of said siphon being connected to a 75 discharge pipe.

3. A vehicle having a tank mounted thereon, a pipe connection extending from within the tank to a discharge point, a chamber at the bottom of the tank constituting a 80 sump with which chamber the inlet end of said pipe communicates, a plate separating the chamber from the interior of the tank, this plate having an opening for receiving the inlet end of said pipe, and a second opening constituting a valve port, and a 85 valve for controlling said port.

4. A device for holding and dispensing liquids comprising a tank having a chamber at its bottom constituting a sump, a 90 discharge pipe communicating with said sump, and means for controlling the flow of liquid from said tank into said sump independent of the flow of liquid from the sump.

5. A device for holding and dispensing liquids comprising a tank provided at its bottom with a chamber constituting a sump, a partition between said tank and said sump, 100 a discharge pipe communicating with said sump, and valve means in said partition for controlling the flow of liquid from the tank independent of the flow of liquid from the sump.

6. A device for holding and dispensing liquids comprising a tank having a chamber at its bottom communicating with the interior of the tank and constituting a sump, means for controlling the flow of liquid from said tank into said sump, said means 110 being independent of the flow of liquid from the sump, and a discharge conduit having one end thereof in communication with said sump, said discharge conduit constituting a siphon. 115

7. A device for holding and dispensing liquids comprising a tank, a chamber at the bottom thereof in communication with the interior of the tank and constituting a sump, a siphon pipe having its inlet end connected to the said chamber and extending upwardly beyond the top wall of the tank and then returning to a point below the bottom of the tank, means for controlling the flow of liquid from the tank into the chamber, and independent means for controlling the flow of liquid from the chamber. 120

8. A device for holding and dispensing liquids comprising a tank, a chamber at the bottom of the tank in communication with 125

the interior thereof and constituting a sump, means for controlling the flow of liquid from the tank to the chamber, a pipe connected to the chamber and extending upwardly beyond the normal liquid level in the tank and then returning to an outlet point below the bottom of the tank, the said pipe constituting a siphon, and means for admitting air to the siphon to break the flow of liquid therethrough.

9. A device for holding and dispensing liquids comprising a tank, a chamber in communication with the tank at the bottom thereof and constituting a sump, a partition

separating the chamber from the interior of the tank, means for controlling the flow of liquid from the tank through the partition into the chamber, a pipe having an intake and connected to the chamber and extending upwardly through the top wall of the tank to a high point from which the pipe leads downwardly to an outlet point below the tank, the said pipe constituting a siphon, and means at the said high point for admitting air to the pipe to break the siphon flow.

In testimony whereof I have hereunto affixed my signature.

EDWIN S. THAYER.
